[57] CLAIM

The ornamental design for a telecommunications switch, as shown.

DESCRIPTION

FIG. 1 is a left front perspective view of a telecommunications switch embodying my new design;

FIG. 2 is a right side elevational view thereof, the left side being a mirror image thereof;

FIG. 3 is a top plan view thereof;

FIG. 4 is a front elevational view thereof;

FIG. 5 is a rear elevational view thereof;

FIG. 6 is a bottom plan view thereof;

FIG. 7 is a right rear perspective view thereof; and,

FIG. 8 is a left, front perspective view on a larger scale of another embodiment of my telecommunications switch, the right side, rear and bottom thereof being the same as depicted in FIGS. 2, 5 and 6, respectively.

FIG. 1

FIG. 2

FIG. 3

FIG. 4

FIG. 5

FIG. 6

FIG. 7

FIG. 8
